HYDRAULIC POWER TRANSMISSION MECHANISM

Filed Oct. 15, 1924

FIG. 1.

FIG. 2.

Inventor,
Antenor Nydqvist
By *Keungorth* att.

UNITED STATES PATENT OFFICE.

ANTENOR NYDQVIST, OF TROLLHATTAN, SWEDEN.

HYDRAULIC POWER-TRANSMISSION MECHANISM.

Application filed October 15, 1924, Serial No. 743,730, and in Sweden October 13, 1923.

The invention relates to fluid power transmission devices, transformers, turbines, compressors or the like.

The hydraulic power transmission device known under the name of the "Föttinger transformer" works, as known, satisfactorily as long as the ratio of gearing for which the device is built is not considerably exceeded. If, however, the turning moment on the driven shaft is increased so that the speed of said shaft is substantially below the speed desired, the efficiency of the system will decrease. The object of this invention is to overcome said difficulty there-
15 by allowing the device to operate on different ratios of gearing.

The invention is characterized, chiefly, by the fact that the blade wheels of the device are provided with blades composed wholly or partially of movable members secured to concentric rings capable of axial displacement, by the displacement of which the operating radial length of blades may be changed to vary the ratio of gearing of the device.

The invention is applicable to water turbines, rotary pumps, gas turbines, compressors and the like enabling a variation of the number of revolutions, the turning moment of turbines, and the pressure and output of pumps and compressors as well.

The invention is illustrated in the drawing by way of example.

Figure 1 is a longitudinal section of one half of a hydraulic transformer according to this invention.

Fig. 2 is a cross section of part of the blade system of said transformer.

Secured to the shaft 1 (the primary shaft) which is connected directly or indirectly to a power engine (not shown) is a blade wheel 2 (the primary wheel), and secured to the shaft 3 to be driven (the secondary shaft) is a blade wheel 4 (the secondary wheel). The wheels 2 and 4 are so positioned relatively to each other as to form within themselves a continuous passage adapted to be filled with liquid which, in the rotation of the primary wheel is caused in well known way both to rotate relatively to the shafts 1 and 3 and to move in the direction of the arrow A, Fig. 1, to thereby give rise to a difference of pressure between inlet and outlet of wheel 2 as in a centrifugal pump. The pressure and movement of the liquid acting on the secondary wheel 4 will

cause said wheel to rotate in the same direction as the primary wheel and thus operate as a turbine.

The parts above described and their opera-
60 tion are characteristic to all Föttinger trans-
formers.

According to this invention, as illustrated in the drawing, the blades of the primary wheel 2 are made in a number of parts. 65 Thus, they comprise, in the embodiment shown, fixed members 6 and axially movable members 7, 7'. The movable members 7, 7' are concentrically arranged and carried by annular disks 8 and 8', respectively, and en- 70 gage corresponding holes formed in the outer side wall of the primary wheel 2. With the movable blade portions 7, 7' pulled out of the blade wheel passage the primary wheel will operate only with the fixed blades 75 6. As the diameter of the latter is com-
paratively small, the speed of rotation of the liquid and thus also the speed of rota-
tion of the secondary wheel 4 will decrease accordingly. According as it is desired to 80 increase the number of revolutions of the secondary wheel, the length of blades of the primary wheel may be increased by pulling the movable blade series into the 85 passage.

The control of the discs 8 and 8', respec-
tively, carrying the movable blade series 7 and 7', respectively, may be effected 90 mechanically or, as indicated in Fig. 1, by hydraulic means. In the said last men-
tioned case the disks are shaped to form 95 closed chambers 10, 11, 12 between them-
selves and the primary wheel and the sur-
rounding casing 9. Said chambers may, through passages 13 formed in the hub of 100 the casing 9 and pipes 14, be set under vari-
ous pressure to displace the disks. The liquid pressure necessary for this purpose may be delivered, for instance, by the de-
vice itself which is completely filled with 105 liquid, through pipe conduits 15, 16 extend-
ing from points having different pressures. The adjustment is effected by means of valves 17 by means of which the chambers 10, 11, 12 may be alternately connected to 105 the discharge side (by 15) or to the suction side (by 16).

In Fig. 1 the middle chamber 11 is assumed to be connected to the discharge side and the two other chambers 10, 12 to 110 the suction side, whereby the disk 8' carrying the outermost blade series 7' is pulled

out. No matter whether the control is mechanical or hydraulical it may be effected while the device is in operation.

Several modifications of the structure described may be made without departing from the principle or scope of the invention.

What I claim is:

1. In a fluid device, a casing, blade wheels in said casing, a fluid channel in said blade wheels, blades on said wheels having a concentric annular series of loose blade sections, individual members carrying each of said loose blade sections, said members being movable axially independently of each other and formed as pistons to enable displacement thereof by means of a pressure medium.

2. In a fluid device, a casing, blade wheels in said casing, a fluid channel in said blade wheels, blades on said wheels having a concentric annular series of loose blade sections, individual members carrying each of said loose blade sections, said members being independently movable axially and having piston-like portions, a closed chamber being provided in the casing for each of said piston-like portions, individual conduits adapted to supply a pressure medium to said chambers, and control valves in said conduits.

In testimony whereof I have signed my name.

ANTENOR NYDQVIST.
